CLAIM

The ornamental design for a vanity mirror, as shown and described.

DESCRIPTION

FIG. 1 is a perspective view of a vanity mirror showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a perspective view of the vanity mirror with environmental straps, in a collapsed position;

FIG. 10 is a perspective view of the vanity mirror with environmental straps, in an expanded position;

FIG. 11 is another perspective view of the vanity mirror in an expanded position; and,

FIG. 12 is another perspective view of the vanity mirror in an expanded position.

The broken lines depict portions of the vanity mirror, and environmental straps, that form no part of the claimed design.

1 Claim, 12 Drawing Sheets
